UNITED STATES PATENT OFFICE.

KARL KALTSCHMID, OF OBERRIEXINGEN, GERMANY.

HEATING-BURNER FOR LIQUID FUEL.

No. 906,237.

Specification of Letters Patent.

Patented Dec. 8, 1908.

Application filed November 4, 1907. Serial No. 400,579.

To all whom it may concern:

Be it known that I, KARL KALTSCHMID, a subject of the King of Würtemberg, and resident of Oberriexingen-an-der-Enz, in the 5 Kingdom of Würtemberg, German Empire, have invented new and useful Improvements in Heating-Burners for Liquid Fuel, of which the following is a full, clear, and exact specification.

10 Bunsen burners for heating which have a round burner head and a straight vaporizer or gasifier extending through the burner head, a construction which is known to combine a satisfactory form of flame with easy 15 access to the interior of the vaporizer, present difficulties in the transference of heat from the flame to the vaporizer.

The present invention relates to a burner of this kind which is similar to the known 20 burners insofar that for transferring the heat a conductor is used which is exposed to the flame and is connected as intimately as possible with the vaporizer but is quite independent of the burner head; in this manner 25 auxiliary flames are obviated and dissipation of heat in the burner by conduction may be avoided.

According to the invention, the heat conductor is so constructed that in spite of its 30 considerable mass, necessary for conducting the heat, and its intimate contact with the flame on the one hand and with the vaporizer on the other, it leaves the space above the burner head completely free and there is 35 no obstacle to the applications of the burner for heating.

In the accompanying drawings Figure 1 is a longitudinal vertical section and Fig. 2 a transverse section of the burner. 40 A liquid fuel reservoir *a* is connected in suitable manner by a pipe with the vaporizer *b*. The latter is a tube passing through the burner head *c* which has the form of an annular chamber. The vaporizer and the duct 45 leading to it may be wholly or partly filled with any suitable material. Fixed to the vaporizer *b* is a bar *d* of good heat conducting metal carrying a plate *e* of like metal, advantageously perforated and in the form of a disk. This plate is in connection with the rest of the burner only through the bar *d* and is not in direct contact with the annular burner chamber *c*. The latter has two rings 50 of flame-openings, an outer one *f* and an inner one *g*.

The burner operates as follows: Spirit, for instance, flows from the reservoir *a* through the duct into the vaporizer *b*, which in starting the burner is preheated by some accessory source of heat. The spirit is vaporized 60 and the vapor passes preferably through a controlling valve *h*, to a nozzle *i* where it is injected under a certain pressure into the burner tube *k*, drawing in air with it through the perforations *l*. The mixture of spirit 65 vapor and air enters the annular chamber *c* and issues through the orifices *f* *g* at which it burns. The flames from the inner flame-openings or orifices *g* play upon the perforated plate *e*, heating it, but for the rest imparting their heat to the vessel to be heated which is supported at a suitable distance 70 above the burner head. The flames from the outer orifices *f* heat the vessel directly. The strongly heated plate *e* imparts by conduction to the vaporizer through bar *d* sufficient heat to maintain the vaporizer at the 75 requisite temperature.

Another advantage of the invention is that the amount of good conducting metal required, in practice copper, is reduced to a minimum, which in view of the cost of such metal is commercially important.

What I claim is:

1. In heating burners for liquid fuel, the 85 combination of an annular burner-head closed at the top, a straight vaporizer extending through said burner-head, a plate of good conducting metal situated within but not in contact with said burner-head, 90 and means connecting said plate with the vaporizer.

2. In heating burners for liquid fuel, the combination of an annular burner-head closed at the top and having inwardly-facing flame-openings, a straight vaporizer extending through said burner-head, a plate of good conducting metal situated within but not in contact with said burner-head, 95 and a bar connecting said plate with the 100 vaporizer.

3. In heating burners for liquid fuel, the combination of an annular burner-head having inwardly and outwardly facing flame-openings, a straight vaporizer extending 105 through said burner-head, a perforated plate of good conducting metal situated within but not in contact with said burner-head, and a bar connecting said plate with the vaporizer.

4. In a vapor-burner, the combination of an annular burner-head closed at the top and having a cylindrical inner wall provided with flame-openings, a straight vaporizing tube extending through said burner-head, and a heating plate located within but out of contact and direct connection with the burner-head and mounted on said vaporizing tube.
- 10 5. In a vapor-burner, the combination of an annular burner-head having a series of inwardly-facing flame-openings, a vaporizing tube extending through said burner-head, and a plate mounted on said tube within said burner-head in the path of the jets issuing from said flame-openings.
- 15 6. In a vapor-burner, the combination of an annular burner-head having a series of inwardly-facing flame-openings, a vaporizing tube, a bar mounted on said tube and located in the opening of said burner-head, and a heating plate for said tube supported solely on and solely in contact with said

bar and heated by the jets from said flame-openings.

25

7. In a vapor-burner, the combination of an annular burner-head having series of inner and outer flame-openings, a vaporizing tube, and a plate mounted on said tube and disposed within the opening of the burner-head, being heated by the jets from the inner flame-openings.

8. In a vapor-burner, the combination of a burner-head having a series of inwardly-facing flame-openings, a vaporizing tube, and a heating plate supported on said vaporizing tube within the burner-head and adjacent said flame-openings.

In testimony, that I claim the foregoing as my invention, I have signed my name in presence of two subscribing witnesses.

KARL KALTSCHEMID.
